UNITED STATES PATENT OFFICE.

STERLING ELLIOTT, OF WATERTOWN, MASSACHUSETTS.

DRILLING-MACHINE.

SPECIFICATION forming part of Letters Patent No. 324,759, dated August 18, 1885.

Application filed July 7, 1884. (No model.)

To all whom it may concern:

Be it known that I, STERLING ELLIOTT, of Watertown, county of Middlesex, State of Massachusetts, have invented an Improvement in 5 Drill-Presses, of which the following description, in connection with the accompanying drawings, is a specification, like letters on the drawings representing like parts.

This invention has for its object the production of a light-running, efficient, and durable 10 drill-press.

In drill-presses as heretofore constructed the wear of the spindle, both in its rotary and longitudinal movements, has been upon the 15 same bearings, which quickly wears the said bearings, and also causes the strain of the driving-belt to interfere with the longitudinal movement of the spindle. In my invention the cone has sleeve-like extensions which 20 enter bearings, and the spindle takes independent bearings in said sleeves.

Figure 1 is a side elevation, partially in section, of a drill-press embodying my invention. Fig. 2 is a sectional detail of the lower end or 25 base of the press, to illustrate the mechanism employed to cause the descent of the drill. Fig. 3 is a detail, partially in section, showing the pin to confine the table-holding arms in place, and Fig. 4 a partial section showing the 30 spring-pin in place in groove 8.

The hollow column A, of any suitable length, has a broad base or foot, A', and at its upper end supports a head, A'', provided with bearing supports or arms a a b b. The arms a a 35 are provided with brass or other suitable boxes or bearings, a' a'', to receive the sleeve-like journal a³ of the hollow shell-like cone C, and the like journal a⁴ of the head c' of the said cone. The upper end of the lower bearing, a', 40 is recessed to receive a rawhide or other washer, c², and also to form an oil-space in which the said washer rests, the small end of the shell-like cone resting upon the said washer.

The chuck D, of usual construction, and 45 adapted to hold a drill of usual shape, is attached in usual manner to the spindle E, which is extended through the hollow sleeve-like journals a³ a⁴ of the cone. The spindle D has fixed to it the driver d, having arms extended 50 to embrace and slide upon guide-rods d' d', connected with the said cone and its head.

Below the driver the spindle D is surrounded

by a spiral spring, d², which, resting at its lower end upon the interior of the cone, acts to support the spindle D and its attached 55 chuck, except when the same is positively depressed to cause the descent of the spindle.

The above chuck has an annulus, e, connected by pivot-screws e' with the forked or yoke-like end of a lever, e², pivoted at e³ on a link, e⁶, pivoted at e⁵ on the frame. The inner 60 end of the lever e² is connected by a rod, f, with the inner end of a lever, f', pivoted at f², and having a sector-like or enlarged end, f³, provided with suitable notches or holes, 2, to 65 be engaged by a pin or bolt, 3, of a hand-lever, g, or a pin or bolt, 4, of a foot-lever, h, each, as herein shown, having its fulcrum on the rod f², which holds the lever f' f³.

The spindle may be forced down by means 70 of either the hand or foot lever, and the connection of each with the sector-like end f³ may be adjusted to suit the requirements of the workman or the work being done.

The shaft m, the cone m' thereon, and the 75 means for driving it, as well as the bed n and the means for adjusting it, are all substantially as usual, except, it may be, as to their exact arrangement.

The cone C will be driven from the cone m' 80 by a belt extended from one to the other, as usual.

The annulus e is kept down upon the top of the chuck D by a collar attached to the spindle in suitable manner. The spring d² has 85 sufficient strength to substantially counterbalance the weight of the spindle and chuck, and the said spring rotates with the spindle, the lower end of the spring resting upon the cone.

The upper end of the spindle is provided 90 with an adjustable stop, r, made as a clamp, which is made to clasp the spindle by the action of a screw, r'. The adjustment of this stop determines the descent of the spindle and drill, and consequently the depth of the hole 95 to be made by the drill or counterbore.

The stem of the table n enters a socket at the end of arms n', having a split hub which embraces and is adjustable both vertically and horizontally on the column A.

The column A is provided with a vertical groove, 8, which receives the inner end of a pin, 9, (shown as a spring-pin,) the said pin being contained in a casing, 12, screwed to

the side of the said hub. The pin 9, when in the groove 8, insures perfect alignment of the center of the table with the center of the chuck. The head of the pin 9 at its under side is provided with a lug, 14, which, when the pin is retracted against the pressure of the spring surrounding it, and partially turned or rotated, rests against the outer end of the eas-
5 ing and acts to keep the pin drawn back, so that the table can be swung about the column as may be desired.

In this my invention the spindle E has only a movement of reciprocation in the sleeve-like bearings of the cone which revolves with it, 15 and the strain of the driving-belt on the cone C does not exert any pressure which forces the spindle against its bearings. The power exerted to force the drill into the work is applied directly to the top of the chuck, and by 20 a lever having its fulcrum close to the column, which results in greatly reducing strain on the parts.

I claim—

1. In a drill-press, the hollow cone having 25 at its ends hollow sleeve-like bearings, combined with a spindle taking its bearings in the said sleeve-like bearings, and means to connect the cone and spindle to revolve in unison, substantially as described.
2. The hollow cone having at its opposite 30 ends hollow sleeve-like bearings and the guide- rods, and the spindle taking its bearings in the sleeves of the cone, combined with the driver arranged to slide on the said guide- 35 rods, substantially as described.

3. The cone and the spindle therein, and means to connect them to rotate in unison, combined with a stop attached to the spindle to limit the descent of the spindle, substantially as described.

4. In a drill-press, the cone, and the spindle having its bearings in the cone, and means to connect the said spindle and cone to revolve in unison, combined with a spring to elevate the spindle, and with a lever to depress the 45 same, substantially as described.

5. The lever f' , having a segmental end, and the rod f , lever e' , and spindle and chuck, combined with a lever adjustably connected with the segmental head or end of the lever 50 f' , to operate substantially as described.

6. In a drill-press, the column provided with a longitudinal groove, the table n , and arm n' to support it, combined with a pin adapted to be placed in or to be withdrawn 55 from the said groove, the pin in the groove causing the alignment of the center of the table with the center of the spindle, and when out of the groove permitting the said arm to be rotated on the column, substantially as de- 60 scribed.

In testimony whereof I have signed my name to this specification in the presence of two sub-scribing witnesses.

STERLING ELLIOTT.
